UNITED STATES PATENT OFFICE.

CLAUDE T. BENDER, OF MARSHALL, TEXAS.

DESIGN FOR A MEAL-TRAY.

46,618.

Specification for Design.

Patented Nov. 3, 1914.

Application filed July 20, 1914. Serial No. 852,069. Term of patent 7 years.

To all whom it may concern:

Be it known that I, CLAUDE T. BENDER, a citizen of the United States, residing at Marshall, in the county of Harrison and State of Texas, have invented a new, original, and ornamental Design for Meal-Trays, of which the following is a specification, reference being had to the accompanying drawing, forming part thereof.

Figure 1 is a plan view of the meal tray,

showing my new design. Fig. 2 is a section on line A—B Fig. 1.

I claim:

The ornamental design for a meal tray, as shown.

CLAUDE T. BENDER.

Witnesses:

JEFF RIGSBY,

WALTER HARRISON.
